UNITED STATES PATENT OFFICE.

RUDOLPH S. HUNZEKER, OF PITTSBURG, PA., ASSIGNOR OF ONE-HALF TO
WM. A. HERRON, RUFUS H. HERRON, AND WM. J. PATTERSON, ALL OF
SAME PLACE.

SPRING AND BRACE.

SPECIFICATION forming part of Letters Patent No. 284,636, dated September 11, 1883.

Application filed December 21, 1882. (No model.)

To all whom it may concern:

Be it known that I, RUDOLPH STUWART HUNZEKER, of Pittsburg, in the county of Allegheny and State of Pennsylvania, have 5 invented certain new and useful Improvements in Springs and Spring-Braces; and I do hereby declare that the following is a full, clear, and exact description of the invention, which will enable others skilled in the art to which it 10 appertains to make and use the same, reference being had to the accompanying drawings, which form a part of this specification.

My invention consists of a brace for taking 15 heavy strains from springs, and thus preventing them from being broken, and also transferring the weight from the middle of the axle toward the wheels, as will be fully understood from the following description and claim.

In the accompanying drawings, Figure 1 is 20 a side view of a double spring having my brace or bed-plate under the lower part of the spring. Fig. 2 represents a single spring attached to a cross-bar. Fig. 3 represents a double spring, with my brace both above and 25 below the same. Fig. 4 is an end view of my brace for springs.

In the application of my spring-brace the 30 center of the spring A may rest on a bolster, B, or on any other suitable support. The same may be held in place by a clip, C, or otherwise, as is well known to the trade.

In Fig. 1 the brace D is made sharp at one end, so as to fit under the spring A, while the

center and shoulder or swell of the spring rests in part upon the bolster B.

In Fig. 3 a modified form of brace is shown, said brace extending to support or embrace both sides of the shoulder or swell of the spring instead of having a sharp end, as in Fig. 1.

The brace D is made with flanges d, which prevent the spring from sliding from its bed on the brace.

A chain, E, or other means may be used to fasten the brace in place.

It is intended that the brace shall come into action when a heavy load is put on the spring.

My braces may be made of rubber, wood, metal, or any other suitable material.

Having described my invention, what I claim 50 is—

The combination, with a spring, A, constructed substantially as shown, and the support or bolster B, of the flanged brace D d, for supporting the swell of the spring, and thus 55 transfer the weight from the middle of the axle toward the wheels when supporting a heavy load, substantially as described.

In testimony that I claim the foregoing as my own I have hereto affixed my signature in 60 presence of two witnesses.

RUDOLPH STUWART HUNZEKER.
